RADIO RECEIVING APPARATUS

Gilbert E. Gustafson, River Forest, Ill., assignor
to Zenith Radio Corporation, Chicago, Ill., a
corporation of Illinois

Application September 19, 1940, Serial No. 357,447

3 Claims. (CL 250—33)

This invention relates to radio receiving apparatus, and more particularly to the provision of conveniently selectable means for adapting such apparatus for varying conditions encountered in the use thereof such as effect variations in the inductance and capacitance in the antenna and in the signal conducting connection therefrom.

The principal object of the invention is to maintain, under varying conditions encountered in the use of radio receiving apparatus, the effective inductance and capacitance in the signal receiving circuit at desired and approximately fixed and known values, other than such variations therein as may be occasioned by the tuning of said circuit.

A further object is to more accurately maintain the alignment between the tuned signal receiving circuit and the other related tuned circuits in radio receiving apparatus.

In the accompanying drawings,

Figure 1 is a rear perspective view of a portable radio set embodying my invention, showing the hinged back panel of the casing thereof in open position to disclose the arrangement of the loop antenna unit and the disposal of the antenna connecting lead-member when the antenna is to be used within the casing, and illustrating the convenient placement of the switch employed in this embodiment of my invention;

Figure 2 is a vertical sectional view, upon an enlarged scale, taken upon the line 2—2 of Figure 1, showing in detail the construction of a simple form of circuit selecting switch which may be used to connect and disconnect other elements comprised in my invention;

Figure 3 is a horizontal sectional view, upon an enlarged scale, taken on the line 3—3 of Figure 1, showing in detail the construction of the switch and indicating the operation thereof;

Figure 4 is a schematic diagram of the antenna circuit arranged according to this embodiment of my invention.

While the invention is herein illustrated and described as embodied in a compactly arranged portable radio receiving set having a loop antenna which may be housed and used within the casing thereof or removed and individually supported apart therefrom, it is to be understood that the usefulness of the invention is not limited to portable receivers or to the particular type of antenna herein shown.

Popular demand requires that commercial radio receiving apparatus be of the single-control

tuner type. This means that all the circuits which are to be tuned in selecting the desired signal must be kept in tracking alignment. This is comparatively easy to effect in all of the circuits with the exception of the circuit of which the antenna is a part. By nature necessarily exposed to the influence of extrinsic interferences and disturbances, the antenna introduces such unpredictable interferences and disturbances in the antenna circuit regardless of its own characteristics. However, where the inductance, capacitance, and resistance characteristics of the antenna itself are subjected to disturbances which can be anticipated, as I shall hereinafter describe, it is highly desirable that provision be made to prevent such intrinsic disturbances from affecting the antenna circuit as far as possible.

In order that my invention may be clearly understood, it may be well to mention that, in properly designed radio receiving apparatus, maintenance of the highest degree of efficiency requires the retention of the inductance, capacitance, and resistance values of the antenna circuit as they were originally computed and tested by the designer of the apparatus of which such circuit is a most important part, so that the original alignment, selectivity, and high signal output of the antenna circuit may be preserved. Correct alignment is necessary in order to obtain high selectivity and high signal output, and all of these are factors in obtaining a high rejection of what are known as image and ghost signals. The advantages obtainable from high selectivity and high signal output of the antenna circuit are generally well known to those familiar with the art. For example, high signal output from the antenna circuit necessitates less amplification for a given speaker volume. Consequently, less power is required and often fewer stages of amplification are necessary. It is also possible to use a much smaller antenna where provision is made to maintain high signal output values. These factors are particularly important if weight or the overall size of the apparatus are restricted, as they are in the designing of portable receivers such as shown in the accompanying drawings. Furthermore, the maintenance of high output values in the antenna circuit in the manner hereinafter described results in a high signal-to-internal-noise ratio.

If the design and arrangement of the antenna may be established, it is relatively simple to determine the values of its resistance, inductance and capacitance and to design the radio receiving apparatus accordingly. However, this invention

tion contemplates allowing the user relative freedom in locating the antenna in relation to the radio receiving apparatus, and in relation to objects extrinsic to the apparatus, in order to meet the varying conditions which may be encountered.

It is well known to those familiar with the art that the capacitance and inductance of an antenna are greatly affected by surrounding objects. This is especially so in radio apparatus 10 having a loop antenna, since the loop antenna is an inductance unit itself and is part of a tuned circuit, therefore changes in the positioning of the loop antenna with respect to adjacent 15 objects may effect changes in its inductance or capacitance, and may seriously disturb not only its characteristics but those of the circuit of which the loop antenna is a part.

Modern types of portable radio receiving sets 20 are provided with loop antennae, and it has been found highly desirable to construct the loop antennae of such sets as removable units, provide them with connecting lead-members of some length, and in each case design and arrange the 25 antenna, the lead-member, and the radio receiving apparatus so that the antenna may be used within the casing of the set or individually supported some distance from the set. One of the 30 reasons for doing this is to permit the receiving apparatus to be used within a signal shielding structure and allow the antenna to be placed in or near a window or opening in said structure.

As may be readily seen, extending the field of 35 use of an extendible loop antenna also extends the field of influencing conditions to which the antenna may be subjected, and, when an extendible loop antenna is part of portable radio receiving apparatus, the field of influencing conditions is even further extended. For example, 40 the portable apparatus may be used in an aeroplane or in a railroad car, with the antenna placed within the window of such plane or car. The portable apparatus may also be used in any signal shielding structure, with the antenna placed at or near an opening in such structure. 45 Moreover, the portable apparatus will often be used with the antenna in position within the cabinet thereof.

As is well known, the effect on the inductance 50 and capacitance of the antenna by an extrinsic body depends on the size of said body, the material of which it is constructed, and the placement of the antenna with relation thereto. Variations in these factors might, in radio receiving apparatus using multiple control tuning means, be 55 exactly compensated for if the operator were experienced. In the single control type, this is impossible, as single control indicates tuning a combination of two or more circuits with a single 60 control means, and if one circuit of the combination varies from alignment with another thereof, additional means must be used for correcting the variation. Therefore, by definition, the tuning would no longer be by a single control means.

It has been found that there are a number of 65 definable major situations under which notable changes are effected in the inductance and capacitance of the antenna, and that situations other than these result only in slight variations 70 in some one of the major situations.

The number of major situations herein considered is based upon the different uses to which the radio receiving apparatus may be put, and upon the type of radio receiving apparatus used.

For portable radio receiving apparatus provided

with an extendible antenna and of the type usually sold to the general public for the reception of commercial programs, it has been found that three situations cover the major inductance and capacitance changes.

These three situations may be described as follows: The first is characterized by the placement of the antenna and the antenna connecting member in the casing of the apparatus. In the second, the antenna is extended but not placed 10 in immediate proximity to a current-carrying metallic object. In the third, the antenna is extended and placed in close proximity to a current-carrying metallic object or metal-surrounded aperture in a shielding structure, such 15 as the window of a plane or railroad car.

The inductance changes in the first and third mentioned situations are very similar. The close proximity to the metal, either of the metal window frame (as in situation three) or the chassis 20 of the apparatus (as in situation one), lowers the inductance of the antenna, as compared to situation two. The conditions which materially change the capacitance of the antenna and the antenna circuit are unchanged in the second and 25 third mentioned situations. It has been found that the capacitance is lower when the antenna and the antenna connecting lead are positioned within the casing than when they are removed and extended therefrom. Therefore the capacitance of the antenna and the antenna circuit is 30 lower in situation one than in situations two or three.

One means of carrying out my invention is shown in the accompanying drawings, in which 35 the antenna is indicated by reference numeral 1 in Figures 1 and 4, and the antenna connecting member by reference numeral 2. The antenna connecting member enters the chassis 3 of the radio apparatus as indicated at 4. The switch 40 5 in Figure 1 is shown in greater detail in Figures 2 and 3. The contacts 6, 7 and 8 of the switch 5 are shown in Figures 3 and 4. Also shown in Figures 2 and 3, is a ball member 9, operable to connect the contacts 6 and 7 or 1 and 8. The ball member 9 is shown schematically in Figure 4 in three possible positions, namely a, a', a''. 10 and 11 are the tuning condenser and trimming condenser, respectively; 12 and 13 indicate two inductance coils; 14 indicates the condenser of 50 the compensating device; 15 the grid of the first tube of the radio receiving apparatus; and 16 the connection to ground.

Other means than the switch shown may be used to control the circuit. It is possible, for example, to employ the well-known phone-jack plug-and-socket connections. Then the choice of 55 sockets would be similar to the choice of positions of the three-position switch herein shown.

The operation of my invention is as follows: 60 The ball member 9, when placed in the position indicated by a in Figure 4, connects the compensating condenser 14 into the circuit, in parallel with the tuning and trimming condensers, 10 and 11, thereby conditioning the antenna circuit for 65 the first of the situations previously described, the extra capacitance 14 being added, since, as previously mentioned, the capacitance of the antenna and the antenna circuit is lower in situation one than in situations two or three.

When the ball member 9 is in position a', the condenser 14 and the inductance unit 13 are not 70 in the circuit, and the circuit is adjusted for the second previously mentioned situation, wherein the antenna is extended but not placed in imme- 75

diate proximity to a current-carrying metallic object, the inductance of the antenna and the antenna connecting lead being normal.

5 When the ball member 9 is in position *a'*, the circuit is adjusted for the third previously mentioned situation, both inductance units 12 and 13 are in the circuit, as they were in situation one, the proximity of the loop antenna to a current-carrying metallic body being somewhat similar, but condenser 14 is not in the circuit, since the loop antenna is in extended position, away from the chassis of the apparatus.

10 Having fully described my invention and the manner of its use, I claim—

15 1. In radio receiving apparatus, the combination, with a tunable antenna circuit comprising an antenna variably positionable at will with respect to said apparatus, and an antenna lead connecting said antenna with said apparatus, wherein changes in the positions of said antenna and antenna lead with respect to said apparatus effect variations in the characteristics of said circuit, of means acting upon connection with said circuit to compensate for such variations comprising a capacitance element and adjustable means operable to connect said element with and disconnect it from said circuit at will.

20 2. In radio receiving apparatus, the combination, with a tunable antenna circuit comprising an antenna variably positionable at will apart from said apparatus and with respect to objects

25 having an inductive effect upon said antenna, and an antenna lead connecting said antenna with said apparatus, wherein changes in the positions of said antenna and antenna lead with respect to said objects effect variations in the characteristics of said circuit, of means acting upon connection with said circuit to compensate for such variations comprising an inductance element and adjustable means operable to connect said element with and disconnect it from 10 said circuit at will.

3. In radio receiving apparatus, the combination, with a tunable antenna circuit comprising an antenna variably positionable at will both with respect to said apparatus and apart from 15 said apparatus with respect to objects having an inductive effect upon said antenna, and an antenna lead connecting said antenna with said apparatus, wherein changes in the positions of said antenna and antenna lead both with respect to said apparatus and apart from said apparatus with respect to said other objects effect variations in the characteristics of said circuit, of a capacitance element and an inductance element each acting upon connection with and disconnection from said circuit to compensate for such variations, and adjustable means operable at will to simultaneously effect the connection of said capacitance element and the disconnection of 25 said inductance element with and from said circuit and vice versa.

GILBERT E. GUSTAFSON.
